FIG. 1.

FIG. 2.

FIG. 3.

FIG. 4.

FIG. 5.

FIG. 6.

FIG. 7.

FIG. 1 is a perspective view of a boat, showing my new design, taken from the left front;

FIG. 2 is a top plan view thereof;

FIG. 3 is a side elevational view thereof;

FIG. 4 is a bottom plan view thereof;

FIG. 5 is a front elevational view thereof;

FIG. 6 is a rear elevational view thereof; and

FIG. 7 is a perspective view of the boat, taken from the left rear thereof.

The dominant features of my design reside in the portions shown in full line.

The broken line showing of an outboard motor in FIGURES 1 and 7 is for illustrative purposes only.

I claim:

The ornamental design for a boat, substantially as shown and described.
